Kenneth A. Wood, South Euclid, Ohio, assignor
to Bailey Meter Company, a corporation of
Delaware

Application October 17, 1950, Serial No. 12,606

Term of patent 14 years

(Cl. D52—1)

To all whom it may concern:

Be it known that I, Kenneth A. Wood, a citizen of the United States, residing at South Euclid, in the county of Cuyahoga, State of Ohio, have invented a new, original, and ornamental Design for a Control Instrument, of which the following is a specification, reference being had to the accompanying drawing, forming part thereof.

Fig. 1 is a side elevation of a control instrument, showing my new design.

Fig. 2 is a front elevation thereof.

The essential features of the design are shown in full lines.

I claim:

The ornamental design for a control instrument, substantially as shown and described.

KENNETH A. WOOD.
